Primary Examiner — Mitchell Siegel

(74) *Attorney, Agent, or Firm* — Goodman, Allen & Filetti, PLLC; Matthew R. Osenga

(57) **CLAIM**

The ornamental design for a cork grip for golf putters, as shown and described.

DESCRIPTION

FIG. 1 is an isometric view of a first embodiment of the invention.

FIG. 2 is a front view of a first embodiment of the invention.

FIG. 3 is a rear view of a first embodiment of the invention.

FIG. 4 is a left view of a first embodiment of the invention.

FIG. 5 is a right view of a first embodiment of the invention.

FIG. 6 is a bottom view of a first embodiment of the invention.

FIG. 7 is a top view of a first embodiment of the invention.

FIG. 8 is an isometric view of a second embodiment of the invention.

FIG. 9 is a front view of a second embodiment of the invention.

FIG. 10 is a rear view of a second embodiment of the invention.

FIG. 11 is a left view of a second embodiment of the invention.

FIG. 12 is a right view of a second embodiment of the invention.

FIG. 13 is a bottom view of a second embodiment of the invention; and,

FIG. 14 is a top view of a second embodiment of the invention.

The broken lines showing the shaft, as seen in FIGS. 1 and 8, form no part of the claimed design.
